UNITED STATES PATENT OFFICE.

THOMAS I. TAYLOR, OF NEWTON, MASSACHUSETTS, ASSIGNOR TO TAYLOR MACHINERY COMPANY, OF BOSTON, MASSACHUSETTS, A CORPORATION OF MASSACHUSETTS.

WATER GAUGE FOR AUTOMOBILE RADIATORS.

1,421,615.

Specification of Letters Patent.

Patented July 4, 1922.

Application filed June 14, 1921. Serial No. 477,367.

To all whom it may concern:

Be it known that I, THOMAS I. TAYLOR, a citizen of the United States, residing at Newton, in the county of Middlesex and State of Massachusetts, have invented new and useful Improvements in Water Gauges for Automobile Radiators, of which the following is a specification.

This invention relates to water level indicators or gauges which are particularly designed for application to automobile radiators, so that the driver may be informed at all times by visible means from his position when driving, whether or not the radiator water supply is in need of replenishment.

The structure in which this indicator is embodied is designed for attachment to the radiator in place of the usual filling nozzle cap, but is so designed that it does not hinder in any way the action of filling the radiator, and even makes such action easier than the ordinary filling operation. Furthermore it is so designed that the delicate movable parts are protected by a rugged surrounding structure from injury, such as might be caused, for instance, by a robe thrown over the radiator to protect the water from freezing in cold weather.

30 The indicator also provides a surface exposed to the air for condensing vapor arising from the heated water and returning it to the radiator; and it is moreover, an ornamental adjunct to the car.

35 For a full explanation of this invention, together with further objects and advantages, and of all its details and combinations of parts, reference may be had to the accompanying drawings illustrating an embodiment thereof, in which—

Figure 1 is a front elevation partly broken away of the indicator.

Figure 2 is a central vertical section on line 2—2 of Figure 1.

45 Figure 3 is a plan view.

Referring to these drawings at 1 is indicated a filling member having at its lower end a threaded connection 2 for engagement with the usual threaded filling opening or 50 nozzle of the radiator. This member terminates at its upper end in an outwardly flar-

ing funnel portion 3, and between its ends it is widened and formed with a central open space 4 which extends all the way through it. At each side of the open space 55 the member is formed with internal passageways 5 which merge together at both the upper and lower ends of the member, and the inner wall 6 of which provides the boundaries of the open space. Essentially the 60 filling member is a hollow annular body with a threaded flange at one end and a funnel at the diametrically opposite end. It is preferably approximately circular in outline between the threaded flange and funnel, 65 but might have various other forms. The interior open space surrounded by a strong and rigid structure is, however, an important item of the appliance.

From the inner wall 6 of the annular body 70 at the upper part of such wall there rises a web or boss 7 which gives support to a strainer 8 extending across the outlet from the funnel. Various modes of securing the strainer may be provided, but I prefer to 75 secure it by providing on the end of the boss 7 a teat which is passed through a hole in the strainer and is headed over the material of the strainer surrounding such hole.

From the lower part of the inner wall of 80 the body there extends a web or stem 9 which is preferably in the axis of the threaded flange 2 and encloses a passageway 10 opening through the wall 6. This stem has a length sufficient to guide a rod 11 with 85 freedom for the latter to move endwise and without liability of it to bind. The passage 10 is a guideway for this rod.

The body or member 1 is most conveniently made as a metal casting, and it can be 90 thus made of any of the metals used for structural or ornamental work. It may also be cast or molded from non-metallic materials which are susceptible of being cast or molded.

95 The lower end of the rod 11 is secured to a float 12 adapted to be supported by water in the radiator, and its upper end extends into the open space 4 to serve as, or carry, an indicator. Preferably the indicator is a 100 ball or knob 13 made fast to the rod, in order that it may be conspicuous enough to fur-

nish a visible indication to the driver as to the height of water in the radiator. So long as there is plenty of water in the radiator, the ball 13 will be and remain above the bottom of the open space 4, or up to its upper limit of motion, which is shown in dotted lines in Figure 1, and when the water level becomes low the ball will descend toward the position shown in full lines in this figure.

The member 1 furnishes a supporting and protecting housing for the indicator so that it will not be damaged by ordinary causes, such as by throwing a robe over the radiator as is customary in cold weather to prevent the water from freezing.

The passages 4 have extended wall surfaces exposed on all sides to the atmosphere, and so furnish a condensing surface for vapors arising from the heated water within the radiator. The vapors are condensed on the inner surfaces of these walls and drain back within the radiator. The upper end of the funnel is preferably left open so that the radiator may be filled readily when desired. No cap is necessary because the shape and disposition of the water passages baffle the tendency of the water to slop out with the agitation which is caused by the car equipped with the device traveling over rough ground. And the omission of a cap is a great convenience to the motorist as it avoids the necessity of the troublesome removal and replacement of the cap every time the radiator needs filling. The inconvenience of handling the ordinary filling nozzle cap is sometimes serious, particularly when the radiator is hot. Then again the absence of a cap allows the uncondensed vapor arising from the radiator water to pass out into the open air, and the appearance of this vapor gives an indication to the driver as to whether or not the circulating water, and consequently the engine, is becoming overheated.

Having thus described the embodiment of this invention it should be evident that many changes and modifications might be made therein without departing from its spirit or scope as defined by the appended claims.

I claim:

1. A water level indicator comprising a member supportable from the filling opening of an automobile radiator and having an opening transversely therethrough, and also having a water passage in the wall bounding such opening, a float adapted to be supported by water in the radiator, and an indicator exposed within the opening of said member in operative connection with said float to be raised and lowered by corresponding movements of the latter.

2. A water level indicator comprising a radiator supply member having a pair of

water passageways spaced apart intermediate their ends to form a transverse opening, a guideway centrally disposed at the lower ends of said passageways, a float adapted to be supported by water in the radiator, an indicator positioned in said transverse opening, and a rod attached at its lower end to said float, extending upwardly through said guideway and supporting the indicator at its upper end.

3. A water level indicator comprising a filling member adapted to be attached to the water supply opening of an automobile radiator, said member having a pair of passageways merging at their upper and lower ends and spaced apart midway and having a transverse opening between said spaced portions, a vertically perforated web in the lower end of said passageways, the perforation opening at its top into said transverse opening, a rod slidable in said perforation, a float carried by the lower end of said rod and adapted to be supported by water in the radiator, and an indicator carried by the upper end of said rod within said transverse opening.

4. A device of the class described comprising a hollow annular filling member adapted to be attached to the water supply opening of a radiator and having a funnel at its upper end, a boss extending upwardly from the upper part of the inner wall of said member toward said funnel, a strainer secured to said boss and crossing the passage through said funnel, said member having an interior transverse opening and a passage in the wall which bounds said opening, a stem having a central perforation disposed at the lower end of said member, said perforation communicating with said transverse opening, a float adapted to be supported by water in the radiator, a rod extending upwardly from said float and through said perforation, and an indicator positioned within said transverse opening and fixed to the upper end of said rod.

5. A device of the class described comprising a filling member adapted to be attached to the water supply opening of a radiator and having a funnel-shaped open upper end, a web extending upwardly to the base of said funnel-shaped portion and defining a pair of passageways spaced apart between their ends, said member having an opening transversely therethrough between said passageways, a stem having a central perforation disposed at the lower end of said passageways, said perforation communicating with said transverse opening, a float adapted to be supported by water in the radiator, a rod extending upwardly from said float and through said perforation, an indicator positioned within said transverse opening and fixed to the upper end of said

rod, and a strainer supported on said first-mentioned web within the base of said funnel.

6. An attachment for automobile radiators comprising a hollow annular body with a space-enclosing flange at one end of a diameter adapted to be mounted on the filling nozzle of such radiator, and having a re-

ceiving opening in its outer wall near the opposite end of the same diameter; such opening and the space within said flange communicating with the hollow interior of said body.

In testimony whereof I have affixed my signature.

THOMAS I. TAYLOR.
